(57) **CLAIM**

The ornamental design for a fishing lure box, as shown and described.

DESCRIPTION

FIG. 1 is a front elevational view of a fishing lure box showing my new design;

FIG. 2 is a rear elevational view thereof;

FIG. 3 is a left side view thereof;

FIG. 4 is a right side view thereof;

FIG. 5 is a top plan view thereof;

FIG. 6 is a perspective view thereof;

FIG. 7 is a second perspective view thereof;

FIG. 8 is an enlarged view of portion 8 shown in FIG. 1;

FIG. 9 is an enlarged view of portion 9 shown in FIG. 1;

FIG. 10 is an enlarged view of portion 10 shown in FIG. 1;

FIG. 11 is an enlarged view of portion 11 shown in FIG. 2;

FIG. 12 is an enlarged view of portion 12 shown in FIG. 2;

FIG. 13 is an enlarged view of portion 13 shown in FIG. 2;

FIG. 14 is an enlarged view of portion 14 shown in FIG. 3;

FIG. 15 is an enlarged view of portion 15 shown in FIG. 4;

FIG. 16 is an enlarged view of portion 16 shown in FIG. 4;

FIG. 17 is an enlarged view of portion 17 shown in FIG. 5;

FIG. 18 is an enlarged view of portion 18 shown in FIG. 5;

FIG. 19 is an enlarged view of portion 19 shown in FIG. 5;

FIG. 20 is an enlarged view of portion 20 shown in FIG. 5;

FIG. 21 is an enlarged view of portion 21 shown in FIG. 5;

FIG. 22 is an enlarged view of portion 22 shown in FIG. 5;

FIG. 23 is an enlarged view of portion 23 shown in FIG. 6;

FIG. 24 is an enlarged view of portion 24 shown in FIG. 6;

FIG. 25 is an enlarged view of portion 25 shown in FIG. 6;

FIG. 26 is an enlarged view of portion 26 shown in FIG. 7;

FIG. 27 is an enlarged view of portion 27 shown in FIG. 7;

and,

FIG. 28 is an enlarged view of portion 28 shown in FIG. 7.

The broken lines illustrate boundaries of the fishing lure box

and lead lines that do not form part of the claimed design.

1 Claim, 28 Drawing Sheets
